UNITED STATES PATENT OFFICE.

FREDERIC H. RAUH, OF SOUTH ORANGE, NEW JERSEY, ASSIGNOR TO J. WISS & SONS COMPANY, OF NEWARK, NEW JERSEY, A CORPORATION OF NEW JERSEY.

DESIGN FOR A PAIR OF SCISSORS.

53,607.

Specification for Design.

Patented July 15, 1919.

Application filed March 10, 1919. Serial No. 281,861. Term of patent 14 years.

To all whom it may concern:

Be it known that I, FREDERIC H. RAUH, a citizen of the United States, residing at South Orange, in the county of Essex and State of New Jersey, have invented a new, original, and ornamental Design for a Pair of Scissors, of which the following is a specification, reference being had to the accompanying drawing, forming part thereof.

In the drawings Figures 1 and 3 are views of opposite sides and Fig. 2 is an edge view of a pair of scissors, showing my new design.

I claim:

The ornamental design for a pair of scissors, as shown.

FREDERIC H. RAUH.

Witness:

AGNES SCHAEFER.
